United States Patent Office

Des. 220,563
Patented Apr. 27, 1971

220,563

BOTTLE

Franklin Douglas Northgrave, Arva, Ontario, Canada, assignor to London Winery Limited, London, Ontario,
Canada

Filed Nov. 17, 1969, Ser. No. 20,155

Term of patent 14 years

Int. Cl. D9—01

U.S. Cl. D9—168

FIG. 1 is an elevational view of a bottle showing my new design, the opposite side being the same in appearance;

FIG. 2 is an elevational view looking from the right of FIG. 1, the opposite side being the same in appearance;

FIG. 3 is a top plan view; and

FIG. 4 is a bottom plan view thereof.

I claim:

The ornamental design for a bottle, as shown and described.
